UNITED STATES PATENT OFFICE.

JOSEPH W. SCHLOSS, OF NEW YORK, N. Y.

BUTTON.

No. 866,817.

Specification of Letters Patent.

Patented Sept. 24, 1907.

Application filed March 25, 1907. Serial No. 364,482.

To all whom it may concern:

Be it known that I, JOSEPH W. SCHLOSS, a citizen of the United States, residing at the city of New York, in the county of New York and State of New York, have 5 invented certain new and useful Improvements in Buttons, of which the following is a full, clear, and exact description.

My invention relates to soft or flexible buttons of the sort which are used on ladies' cloaks and garments, and 10 which are made in varying sizes and shapes.

Buttons of the above class have been made in the past by taking a small wad or ball of cotton or soft substance, and crocheting a cover thereabout. This produces a button which is very soft and spongy in its texture, which are the trade requirements in this class of goods. It is, however, an operation of considerable difficulty to make the buttons accurately and expeditiously in this way. The tuft or wad of cotton which forms the core is liable to vary in size, density and 15 shape, since all these factors are determined separately and individually for each button made, and by no other guide than the eye or judgment of the workman or girl who makes these buttons. It is clear that even if exactly the same amounts of cotton are obtained 20 for two buttons, that the buttons are not necessarily therefore alike when completed, because one tuft or wad of cotton may be compressed more tightly than the other, or drawn into a different shape. It will be further evident that even if the tufts or wads of cotton 25 can be brought into the same conditions of shape, size and density, that it is difficult to crochet a cover properly about an object of such uncertain characteristics and dimensions.

In carrying out the present invention I aim to overcome all of these difficulties by the use of cores or fillers which are of uniform size, shape, texture, weight and density, which have sufficient stability of form to enable the crocheting processes to be readily accomplished, but which nevertheless produce a button 30 which is very soft and spongy, and which has all the characteristics required by the trade in this class of goods.

With these objects in view, the invention consists in the features of construction and combination herein- 35 after set forth and claimed.

In the drawings: Figure 1 shows a button core or filler embodying the principles of my invention; Fig. 2 shows the completed button; Fig. 3 shows how a composite core is formed; and Fig. 4 shows the completed 40 button of rounded or globular shape produced thereby.

Referring to the drawings in which like parts are designated by the same reference sign, 1 indicates a disk of felt or other spongy but coherent substance, which is conveniently made by punching out circular

portions from a flat sheet of the material of proper thickness. While these disks are very soft and flexible and spongy, it is evident that they have nevertheless a definite shape to which they return after deformation in the manner of felt and analogous coherent spongy substances generally. These characteristics of having great softness and flexibility, and at the same time having a definite shape under normal conditions I regard as the important ones for the button core or filler employed by me. Since the disks are all stamped from sheets of felt of uniform texture and thickness, it is evident that they are exactly alike in all matters of form, size, texture, density and weight, as required. With a core or filler of this sort it is merely necessary to crochet the cover 2 thereon, which can be readily done in view of the definite shape of the core or filler, as above mentioned. The resulting buttons (shown in Fig. 2) are therefore uniform in all respects, but have all the softness and sponginess which is inherent in felt or similar substances which constitutes their core.

In Fig. 3 I have illustrated how large or globular buttons can be readily made in accordance with my invention.

3 and 4 denote disks of felt which may be of the same or different sizes and which are superposed upon one another. As many of these disks may be used as necessary, and they may vary progressively in size so as to form an approximate sphere in some cases. When a cover 5 is crocheted over this composite core, a spherical button is developed, which is very soft and spongy. The buttons produced in this way are absolutely uniform in all respects, and this uniformity is secured without any especial difficulty for the reasons above described. The covers can be crocheted over the buttons having composite cores or fillers as readily as with those in which a single disk is used. While I have described the covers of these buttons as crocheted in place, it is evident that they may be of various fabrics and applied in any desired way.

What I claim, is:—

1. A button having a core of spongy but coherent material, and a fabric cover therefor, said cover directly enveloping said core and depending solely thereon for its support and shape. 95

2. A button having a core of spongy but coherent material cut to a predetermined shape, and a cover crocheted over the same, said cover directly enveloping said core and depending solely thereon for its support and shape. 100

3. A button having a core formed of a disk of spongy but coherent substance of uniform thickness, and a cover crocheted over the same, said cover directly enveloping said core and depending solely thereon for its support and shape. 105

4. A button comprising a felt disk having a cover crocheted thereon, said cover directly enveloping said disk and depending solely thereon for its support and shape. 110

5. A button comprising a plurality of disks of spongy

but coherent substance having a cover crocheted thereon, said cover directly enveloping said disks and depending solely thereon for its support and shape.

6. A button comprising a plurality of felt disks having a cover crocheted over the same, said cover directly enveloping said disks and depending solely thereon for its support and shape.

7. A button comprising a core or filler of flexible coherent material of definite form and a cover for the same,

said cover directly enveloping said core and depending 10 solely thereon for its support and shape.

In witness whereof, I subscribe my signature, in the presence of two witnesses.

JOSEPH W. SCHLOSS.
